GAME BOARD

Guadalupe Rojo, North Chicago, Ill.
(1015 Lenox, Waukegan, Ill.)

Filed Sept. 25, 1963, Ser. No. 76,731

Term of patent 14 years

(Cl. D34—5)

The figure of the drawing is a top plan view of a game board showing my design. The board is of conventional thickness.

The dominant features of my design reside in the portions shown in full lines.

I claim:

The ornamental design for a game board, substantially as shown and described.
